UNITED STATES PATENT OFFICE.

LEROY RAYMOND KAIN, OF LOS ANGELES, CALIFORNIA.

DESIGN FOR A LEG FOR A DISPLAY STAND OR SIMILAR ARTICLE.

Application filed January 2, 1929. Serial No. 29,471. Term of patent 3½ years.

To all whom it may concern:

Be it known that I, LEROY RAYMOND KAIN, a citizen of the United States, residing at 113 West Ann St., Los Angeles, in the county of Los Angeles and State of California, have invented a new, original, and ornamental Design for a Leg for a Display Stand or Similar Article, of which the following is a

specification, reference being had to the accompanying drawing, forming part thereof.

The figure is a perspective view of a leg for a display stand, showing my new design.

I claim:

The ornamental design for a leg for a display stand or similar article, as shown.

LEROY RAYMOND KAIN.
